UNITED STATES PATENT OFFICE.

JOHN F. GORMAN, OF PORTLAND, OREGON, ASSIGNOR, BY MESNE ASSIGNMENTS, TO
A. J. KIRSTIN COMPANY, OF ESCANABA, MICHIGAN, A CORPORATION OF MICHIGAN.

STUMP-PULLER.

1,348,940.

Specification of Letters Patent.

Patented Aug. 10, 1920.

Application filed May 3, 1916, Serial No. 95,109. Renewed January 17, 1920. Serial No. 352,231.

To all whom it may concern:

Be it known that I, JOHN F. GORMAN, a citizen of the United States, residing in the city of Portland, county of Multnomah, and 5 State of Oregon, have invented certain new and useful Improvements in Stump-Pullers, of which the following is a specification.

My invention relates to stump pullers, and more particularly to portable stump 10 pullers which can be readily moved from place to place and operated by means of a hand lever for winding up a cable attached to a stump which is to be pulled out of the ground, although, of course, it is to be understood that my device can be used for 15 winding up a cable hitched to any object which it is desired to move.

Among the salient objects of my invention are,—to provide in a device of the character 20 referred to, means whereby the operating drum can be unwound, step by step, by means of an operating hand lever, when said drum is under strain on the cable, and to provide an improved and simplified construction and arrangement which will 25 cheapen the cost of manufacture, will strengthen the device, will provide a third speed for operating the drum without complicating or materially increasing the cost 30 of the device, and which will make it possible to readily take the device apart, or to assemble it for any purpose whatsoever.

In order that others may understand my invention I have shown a practical embodiment thereof in the accompanying two 35 sheets of drawings which I will now describe.

Figure 1 is a top plan view of my invention with the operating pawls, or dogs, removed;

40 Fig. 2 is a vertical sectional view through the invention taken on line 2—2 of Fig. 1, with one set of pawls shown in place;

Fig. 3 is an inside view of the side member, shown in edge view at the top of Fig. 45 1, showing the pawl-actuating mechanisms attached to the inside of said side member;

Fig. 4 is a detail view through Fig. 3, taken on line 4—4;

50 Fig. 5 shows top and side views of a T-bolt for holding the pawls in their seats; and

Fig. 6 is a detail sectional view taken on line 6—6, Fig. 1, with pawls in place, showing a slightly modified form of T-bolt for

holding the pawls which operate upon the 55 third speed gear.

Referring now more in detail to the drawings, my invention comprises in combination two side members 1 and 2, the general form of which will be clearly seen from Fig. 3, 60 in which is shown the inside of one of said members, each of said side members being provided with a drum receiving bearing socket 3, an operating shaft socket 4, a take-up block socket 5, and an axle socket 6. 65 At the axle socket 6, each of said side members is provided on its outside with a sleeve bearing lug, as 6^a, for a purpose hereinafter referred to. Rotatably mounted in the drum socket 3, is a drum 7, having formed as a 70 part thereof at one side, a gear 8, and having formed as a part thereof at its opposite side, a gear 9, said gears being slightly of convexed form on their adjacent, or inner, sides, as at 8^a and 9^a, which prevent wearing 75 contact between the cable and the edges, or rims, of the gears. Said drum is also provided with a cable receiving socket 7^a, adjacent to which, said drum is made somewhat thicker, as at 7^b, whereby as the cable 80 passes around the drum from said socket 7^a, it will not rest directly upon the cable hook, but will run upon the heavy portion 7^b of the drum, which will take the strain of the cable and thus prevent a strain being applied 85 to the cable at its point of attachment. Said drum 7, is hollow and has formed at its opposite ends sleeve-like bearing extensions 7^c—7^d, which are inserted in the bearing sockets 3—3, in the side members 1 and 2, 90 the sleeve extension 7^c, being provided on its outer edge with ratchet teeth 7^e, adapted to mesh with corresponding ratchet teeth 10^a, formed on the inner end of an operating member 10, which operating member has a 95 square shank portion, as indicated, to receive an operating lever, and which operating member 10 is mounted upon and keyed to a shaft 11, which extends into the hollow drum through the sleeve extension 7^c thereof, and 100 is provided with a spring 12, shown in dotted lines in Fig. 1, said spring bearing at its inner end against a washer 13, held in place by a pin 14, through the inner end of the shaft 11. At its outer end, said spring bears 105 against the inner end of the sleeve extension 7^c, of the drum, as at 15, whereby said spring operates to draw said shaft 11, in-

wardly, and to hold the ratchet member 10, in operating engagement with the ratchet teeth 7^e, on the sleeve extension 7^e of the drum 7. Thus by applying the operating lever to the shank 10, of said operating member, the drum 7, can be turned directly, the operating member 10, operating as a ratchet, when turned backwardly, and turning the drum with it when turned forwardly. 10 The operating ratchet member 10, being carried by the sleeve bearing portion 7^e, of the drum 7, is readily inserted through the bearing socket 3. Mounted through the axle sockets 6—6^a, and through their sleeve lugs 6^a—6^a, is a bolt 16. A pipe, or spacing sleeve, 17, shown in section in Fig. 2, is placed on said bolt 16, between the side members 1 and 2. The sleeve lugs 6^a—6^a, on the members 1 and 2, receive thereon the wheels 18—18. Said bolt is held in place by a nut 19. Thus by removing the nut 19, the bolt 16, can be withdrawn, which permits the removal of the wheels 18—18, and also the spacing member, or sleeve 17. 25 Rotatably mounted in the operating shaft bearing sockets 4, of the side members 1 and 2, is a rocker shaft member 20, which projects through the side member 1, and is provided with a square operating shank 21. 30 Said rocker shaft is provided near the side member 1, with two pawl receiving sockets, as 20^a, extending longitudinally of said shaft, with a bolt hole 22, through said shaft 20, between said sockets. At its opposite end, adjacent said side member 2, said rocker shaft is provided with similar pawl sockets 20^b, formed therein, but spaced farther apart than are the sockets 20^a. A bolt hole 23 is also formed through said shaft 20, between the sockets 20^b. 40 24 and 25 designate two operating pawls having their lower ends pivotally seated in the sockets 20^a, as clearly indicated in Figs. 2 and 3. The pawl 24, is provided on its outer face with a cam portion 24^a, and on its inner face with a cam portion 24^b, said pawl 24, being adapted to engage the gear 8, while the pawl 25 engages the same gear directly underneath the pawl 24, wherefore as the rocker shaft 20, is 45 oscillated about its axis, said pawls 24 and 25, are alternately raised and lowered. The pawl 25, has an arm 25^a, which extends back into operating engagement with the cam portion 24^a, on the pawl 24, as clearly indicated in Figs. 2 and 3. Attached to said pawls 24 and 25, are operating rods 26 and 27, provided with washers 26^a and 27^a. Also mounted upon said rods 26 and 27, are springs 28 and 29, which bear at their corresponding ends against the washers 26^a and 27^a, and at their opposite ends bear against a lever 30, through which said rods 26 and 27 pass, said lever 30, being pivotally attached at its lower end, as at 31, to the inside of 50 the side member 1, and at its upper end being

provided with a dog 32, pivotally attached thereto and adapted to seat in a notch 33, formed in the upper edge of the side member 1, as clearly indicated in Fig. 3. A coiled spring 34, is attached at one end, as at 55 35, to the inside of the side member 1, and at its opposite end to the lever 30, as at 36. When said lever 30, is pressed forwardly, in the position shown in full lines in Fig. 3, with the dog 32, bearing in the notch 33, 75 in the side member 1, the spring 34, is out of commission, and the springs 28 and 29, operate on the rods 26 and 27, tending to press the pawls 24 and 25, outwardly, away from the gear 8. If the lever 30, is released by 80 lifting the dog 32, out of the notch 33, then the spring 34, operates to draw the lever 30, rearwardly, as shown in dotted lines in Fig. 2, said lever 30, engaging the hooked ends 26^b and 27^b, of the rods 26 and 27, whereby 85 said rods 26 and 27 are pulled by the spring 34, thus yieldingly drawing the pawls 24 and 25 into the gear 8.

Referring to Figs. 4 and 5, the pawls 24 and 25, are held in place by means of a bolt 90 37, having a round head 37^a, and passing through a T-member 38, the opposite ends of which are inserted through apertures in the pawls 24 and 25, so that the ends of said T-member 38, rest down upon the rounded 95 ends of said pawls 24 and 25, holding them pivotally in place, as is clearly indicated in Figs. 2, 3 and 4. A spring 39, is mounted upon the bolt 37, on the under side of the operating or rocker shaft 20, which tends to 100 draw said bolt yieldingly downwardly, whereby said pawls 24 and 25 are held under a certain tension which keeps them from becoming loose. Said rocker shaft is provided on its under side with a pair of lugs 105 40 and 41, which are adapted to engage a fixed lug 42, formed on the inner face of the side member 1, whereby the rocking movement of said shaft 20, is limited in each direction. 110

Referring now to Figs. 1 and 6, there is pivotally seated in the sockets 20^b, of the rocker shaft 20, two straight pawls 43 and 44, which are drawn into engagement with the third speed gear 9, by means of rods 45 and 46, in the same manner in which the pawls 24 and 25 are drawn into the gear 8, there being another lever similar to lever 30, and a spring similar to spring 34, on the inside of the side member 2, but which are 115 not shown in the drawings for the reason that the parts are the same as the parts 26, 27, 28, 29, 30, 31, 32, 33 and 34. Said pawls 43 and 44 are held in place by a T-member 47, inserted through openings 43^a and 44^a, 120 in the pawls 43 and 44, and bearing downwardly upon the rounded portions 43^b and 44^b, of said pawls, as clearly indicated in Fig. 6, said T-member 47, being held yieldingly in place by means of a bolt 48, having 125 130

a ball head 49, seated in a suitable socket in said T-member 47, with a spring 50, operating upon the lower end of said bolt 48, in the manner clearly shown in said Fig. 6, for holding said T-member 47, and said pawls 43 and 44, yieldingly in operating positions. As said rocker shaft 20, is rocked, the pawls 43 and 44, if they be set in their operating positions, alternately engage and move for-
wardly the gear 9, indicated in dotted lines.

A take-up block 51, having sleeve lugs 52—52, on its opposite sides, is inserted between the side members 1 and 2, with the sleeve lugs 52 inserted in the bearing sockets 5, in the side members 1 and 2, said take-up block being held in place by means of bolts 53—53, inserted through said sleeve lugs 52—52, and said side members 1 and 2, as clearly indicated in Fig. 1, said take-up block is thus pivotally secured between the side members 1 and 2, and because of the sleeve lugs 52—52, there is no shearing strain on the bolts 53—53. The take-up block 51, is provided with the usual wedge block 54, which is provided with the slot 55, whereby it can be adjusted to secure a cable to the take-up block 51, in a manner which is well understood.

Referring to Fig. 1, I have provided on the inner face of the gear 8, a lug 8^b, the purpose of which is to engage the cable after it has been wrapped around the drum 7, in one layer, for the purpose of causing said cable to start back in another layer toward the opposite gear 9, instead of piling in a miscellaneous manner, thus keeping the cable evenly wound upon the drum 7.

Referring to the take-up block 51, it is provided at its opposite sides with two square lug members 51^a—51^a, adapted to be seated in notches in the small ends of the side members 1 and 2, one of said notches being designated 51^b, Fig. 3. This interlocking between the take-up block 51, and the side members 1 and 2, insures better alinement through the machine and also makes the machine more rigid. It will be noted also that when the cable is inserted in said block around the wedge block 54, the strain on the cable operates to lock the cable by reason of the movement of the wedge block 54, into the reduced portion of the take-up block 51. It will also be evident that the cable can be very quickly taken up by hand adjustment through this take-up block 51, in a manner well understood.

Attention is also called to an important feature in connection with the bolts 37 and 48, and the T-members 38 and 47, which hold the lower ends of the pawls 24 and 25, and 43 and 44, in their respective sockets in the rocker shaft 20. This flexible joint between the bolts 27 and 48, and the T-members 38 and 47, compensates for any unevenness or imperfection in the formation of the

sockets, or of the rounded portions of the pawls, insuring a perfect seating of the pawls and holding them in proper positions without interfering with their free action. This construction also permits for taking up wear under the action of the springs 39 and 50, and thus prevents loosening of the parts.

The operation of my invention may be briefly described as follows:

Assuming that the device has been set in place and is anchored by means of a cable attached to the take-up block 51, and that a cable attached to the stump, or other object to be moved, is attached to the drum 7, said drum may be operated directly by means of an operating lever (not shown), upon the shank 10, of the shaft 11, inserted in the end of the drum sleeve. Thus by operating said lever, said drum is directly turned and the cable wound thereupon, the ratchet mechanism at 10^a, permitting the hitch movements of the operating lever, in a manner well understood. Either set of pawls, 24 and 25 or 43 and 44, may be set to prevent reverse movement of the drum during the hitch movements of the operating lever.

By applying the operating lever to the shank 21, of the rocker shaft 20, said rocker shaft can be oscillated or rocked, and either set of the operating pawls 24 and 25, which operate drum gear 8, or pawls 43 and 44, which operate drum gear 9, can be set for action. These pawls are set for action by releasing the dog 32, upon the upper end of the lever 30, so as to permit said lever 30, to be drawn rearwardly by the spring 34, said lever 30 also operating to yieldingly pull the pawls into the gears 8 or 9, by means of the rods 26 and 27, or the rods 45 and 46, as the case may be. The operation of the pawls 43 and 44, upon the drum gear 9, is alternate and independent of each other, the pawl 44, operating to turn the gear 9, when the rocker shaft 20, is rocked in one direction, and the pawl 43, operating to continue the movement of said drum gear 9, as said rocker shaft is rocked in the opposite direction, these pawls operating upon a second speed gear, 9.

Referring now to the operation of pawls 24 and 25, and assuming that the dog 32, has been lifted out of the notch 33, so that lever 30, is drawn backwardly to spring 34, to the position shown in dotted line in Fig. 2, said pawls 24 and 25 are drawn yieldingly inwardly to the gear 8. As the rocker shaft 20, is rocked in one direction, the pawl 25 advances the gear 8, while the pawl 24, is drawn downwardly one notch. As the rocker shaft 20, is rocked in the opposite direction, the gear 8, is advanced by the pawl 24, while the pawl 25 recedes one notch, and thus, notch by notch, the gear 8 is ad-

vanced, said pawls being drawn inwardly by the connections from the spring 34. This operation is similar to the operation of the pawls 43 and 44, which act on the gear 9.

I will now describe the operation of pawls 24 and 25, when it is desired to back up, or reverse, the direction of gear 8, under strain. The parts are set, as shown in full lines in Fig. 3, with the lever 30, pulled forwardly and the dog 32, set in notch 33, in the side member 1. This action puts spring 34, out of commission and compresses springs 28 and 29 in a way to force the pawls 24 and 25 outwardly, or away from the gear 8. It will be understood, of course, that so long as one of said pawls 24 or 25 is in engagement with a notch of the gear 8, it can not be pressed outwardly by the action of springs 28 or 29. In Fig. 3, pawl 25 is holding the gear 8, against backward movement, that is, in the direction indicated by the arrow. As soon as pawl 25 takes the load on the gear 8, pawl 24 is forced outwardly by its spring 28, the cam portion 24^a, of said pawl 24, preventing said pawl from moving unduly away from the gear. Now as the rocker shaft 20, is rocked so as to allow pawl 25 to move downwardly with the load on the gear 8, the pawl 24, by reason of the engagement of its cam portion 24^a, with the hook or arm 25^a, attached to pawl 25, is being forced inwardly against the tension of its spring 28, until it takes the load one notch back on the gear 8, as it is about ready to do, in the position shown in Fig. 3. As the pawl 24, is thus forced into the gear 8, by the engagement of its cam 24^a, with the arm 25^a, and takes the load on the gear 8, the pawl 25 is pressed outwardly by its spring 29, until it comes in contact with the cam 24^b, on the inner face of the pawl 24. As the rocker shaft 20, is rocked to permit the pawl 24, with its load on the gear 8, to move downwardly, the cam portion 24^b, on the inner face of said pawl 24, engages the back of pawl 25, and forces it inwardly into the gear 8, one notch back of its former position, thus by the alternating movements of the rocker shaft 20 and the pawls 24 and 25, operating upon each other through their cam portions, the gear 8, and the drum 7 can be unwound, or reversed, under strain, to slacken the cable. It will be understood, of course, that this back, or unwinding, movement of the gear 8, notch by notch, can not be done without strain on the drum 7. As soon as the tension is released on the drum 7, and the gear 8, the pawls 24 and 25 are both automatically moved outwardly by their springs 28 and 29, thus giving free movement of the drum and the gear 8.

I am aware that changes in the details of construction and arrangement here shown for purposes of illustration can be made

without departing from the spirit of my invention, and I do not, therefore, limit my invention to this particular embodiment thereof except as I may be limited by the hereto appended claims.

I claim:

1. In a device of the character referred to, in combination, supporting means, a drum rotatably mounted therein and provided with an operating gear, a rocker member, a pair of operating pawls pivotally carried by said rocker member and adapted to alternately engage said gear in an operating manner as said rocker member is rocked, means yieldingly moving said pawls away from said gear, and operating connections between said pawls for alternately and positively moving said pawls into holding engagement with said gear, as said rocker member is rocked.

2. In a device of the character referred to, in combination, supporting means, a drum rotatably mounted therein and provided with a gear, and means for operating said drum comprising a rocker member, a pair of operating pawls mounted thereon and adapted to engage said gear, one above the other, and means whereby one pawl operates upon the other pawl to move it into operating engagement with said gear, for the purpose referred to.

3. In a device of the character referred to, in combination, supporting means, a drum rotatably mounted therein and provided with a gear, a rocker member mounted to be rocked in said supporting means, operating pawls carried by said rocker member, and cam portions formed on one of said pawls with operating connections with the other of said pawls, whereby said pawls are alternately moved by a cam action into operating connection with said gear.

4. In a device of the character referred to, in combination, a supporting means, a drum rotatably mounted therein and provided with a gear, a rocker member mounted to be rocked in said supporting means, operating pawls carried by said rocker member, and means yieldingly moving said pawls away from said gear, and means for positively and alternately moving said pawls into operating engagement with said gear.

5. In a device of the character referred to, in combination, supporting means, a drum rotatably mounted therein and provided with two different speed gears, a rocker member, a pair of operating pawls pivotally carried by said rocker member for each of said gears, said pawls being adapted to be set into operative or inoperative positions relative to their respective gears, as desired, and means for yieldingly moving said pawls into said gears when set in operative positions.

6. In a device of the character referred to,

- in combination, supporting means, a drum rotatably mounted therein and provided with two different speed gears, a rocker member, a pair of operating pawls pivotally carried by said rocker member for each of said gears, said pawls being adapted to be set into operative or inoperative positions relative to their respective gears, as desired, one pair of said pawls being provided with means adapted to be set for yieldingly moving said pawls away from their gear, and operating connections between said pawls for positively and alternately moving them into holding engagement with their gear in opposition to the means for yieldingly moving them away from said gear. 7. In a device of the character referred to, in combination, a pair of side members having bearing sockets formed therethrough opposite each other, a drum having bearing sleeves formed at its outer ends as a part thereof and adapted to be inserted through opposite bearing sockets in said side members, said drum being provided with an operating gear, a rocker member adapted to be inserted through opposite bearing sockets in said side members, said rocker member being provided with operating pawls, means for holding said pawls in or out of operating engagement with said gear, as desired, a take-up block having sleeve lugs inserted in opposite bearing sockets in said side members, and means for securing said side members together at a space apart, substantially as described. 8. In a device of the character referred to, in combination, supporting means, a drum provided with a gear, a rocker member provided with bearing sockets at opposite sides of its axes of rotation, a pair of pawls pivotally seated in said sockets and adapted to operate on said gear, a T-member for holding said pawls in place, and a bolt through said T-member and said rocker member, substantially as described. 9. In a device of the character referred to, in combination, supporting means, a drum provided with a gear, a rocker member provided with bearing sockets at opposite sides of its axes of rotation, a pair of pawls pivotally seated in said sockets and adapted to operate on said gear, a T-member for holding said pawls in place, and a bolt through said T-member and said rocker member, said bolt being provided with a spring, whereby to yieldingly hold said T-member in holding engagement with said pawls. 10. In a device of the character referred to, a pair of side members having formed therein, opposite each other, bearing sockets, and having formed on their outer sides bearing sleeves, wheels mounted upon said bearing sleeves outside of said side members, a bolt through said bearing sleeves, wheels and side members, and provided with a spacing sleeve between said side members, whereby, by removing the bolt, said wheels can be removed from said side members and said side members disconnected from each other, substantially as described. 11. In a device of the character referred to, in combination, a pair of side members provided with bearing sockets opposite each other and also provided on their outer sides with bearing sleeves, wheels mounted upon said bearing sleeves, a cable drum having bearing portions at its opposite ends adapted to be inserted through opposite bearing sockets in said side members, said drum being provided with an operating gear, a rocker member adapted to be inserted through opposite bearing sockets in said side members, said rocker member being provided with operating pawls, means for holding said pawls in or out of operating engagement with said gear, as desired, a take-up block having sleeve lugs inserted in opposite bearing sockets in said side members, and means for securing said side members together at a space apart, substantially as described. 12. In a device of the character referred to, a pair of side members, a take-up block pivotally mounted between said side members, and interfitting connections between the opposite sides of said take-up block and said side members, whereby to hold said take-up block relative to said side members. 13. In a device of the character referred to, in combination, a pair of side members, a cable drum, means for operating said cable drum, a take-up block mounted between said side members, said take-up block having tapering side portions, and a wedge block adjustably mounted between said tapering side portions and adapted to receive a cable therearound and between said side portions and the opposite sides of said wedge block, whereby to adjustably lock said cable in said take-up block, substantially as described. 14. In a stump puller, a frame, a cable winding drum mounted thereon, a cable attaching means pivotally mounted on the frame on an axis parallel with the axis of the drum, and means for limiting the pivotal play of the cable attaching means when in operative position. 15. In a stump puller, a pair of side frames provided with bearings and sockets, means connecting the side frames together, a drum between the side frames mounted in bearings thereof, a cable attaching means having trunnions seated in sockets in the side frames, and bolts passing through the

trunnions and side frames for securing the cable attaching means in place.

16. In a stump puller, a frame, a cable drum mounted thereon, a cable attaching means pivotally mounted on the frame on an axis parallel with the axis of the drum, and lugs on said means engaging said frame for limiting the pivotal play of the cable attaching means.

10 17. In a stump puller, a pair of side frames provided with sockets, bolts connecting the side frames together, a drum between the side frames mounted in bearings

thereof, a cable attaching member having trunnions seated in sockets in the side frames, bolts passing through the trunnions and side frames for securing the cable attaching member in place, and means on said member for engaging the cable. 15

Signed at Portland, Multnomah county, 20 Oregon, this 27th day of April, 1916.

JOHN F. GORMAN.

In presence of—

I. M. GRIFFIN,
J. C. STRENG.
